DESIGN FOR A PIANO

Christian Albert Jacob, Jr., Scarsdale, N. Y.

Application August 9, 1935, Serial No. 58,031

Term of patent 14 years

To all whom it may concern:

Be it known that I, Christian Albert Jacob, Jr., a citizen of the United States and a resident of Scarsdale, in the county of Westchester and State of New York, have invented a new, original, and ornamental Design for a Piano, of which the following is a specification, reference being had to the accompanying drawing, forming a part thereof.

The drawing is a perspective view of a piano illustrating my new design.

I claim:

The ornamental design for a piano, substantially as shown.

CHRISTIAN ALBERT JACOB, JR.
